TURBINE

Jules Georges Nussbaum, Toulouse, France, assignor to Hydro Mecanique, Toulouse, France, a society of France

Application January 22, 1947, Serial No. 723,503
In France April 30, 1946

6 Claims. (Cl. 253—148)

1

The adjustment of the blades of a helical turbine is generally effected by means of an adjusting rod sliding within the turbine shaft which must therefore be made hollow.

If the turbine directly drives an electric generator or any other machine the machine must also have a hollow shaft for the passage of the adjusting rod. This involves a special construction of the driven machine and prevents the use of a standard machine having a solid shaft.

Various arrangements have been proposed for enabling this to be done. That forming the object of the present invention is distinguished by the fact that a member for distributing a liquid under pressure which controls the setting of the turbine blades is placed within the rotating part of the turbine and preferably within a piston controlling the setting of the blades.

In particular the distributor rotates with the turbine shaft, it is in the form of a slide valve sliding within the turbine shaft and it is in the form of a hollow shaft the central part of which communicates by transverse ports with the liquid supply and with one or other face of the piston according to its position in relation to the latter; in its mid position in relation to the piston the distributor connects the liquid supply to both faces of the piston. The distributor is actuated by a member external to the rotating part of the turbine.

By way of example the accompanying drawing shows in Figure 1 in axial section a helical turbine embodying adjusting means in accordance with the invention and in Figure 2, an enlarged axial section of the valve and piston mechanism forming part of the turbine shown in Figure 1.

In the turbine shown in the drawing the setting of the blades is controlled by a piston 100 mounted on the adjusting rod 101 of the turbine runner and working within a cylinder 102 rigid with the vertical shaft of the turbine and rotating with it. Within the piston 100 slides the lower part of a distributing slide valve 103 also rotating with the shaft and of which the upper part slides within the shaft itself journalled in a bearing 369 within which is provided the chamber 109 fed with oil under pressure by a pump 110 drawing from a reservoir 111 and discharging through a pipe 106.

The slide valve 103 is provided with a central chamber 107 fed through ports 108.

The oil is distributed through ports 113 into a feed chamber 112 for the piston formed by a groove in the periphery of the slide valve 103,

2

the width of the groove 112 being such that it can communicate simultaneously with feed chambers 114 and 116 formed by grooves in the wall of the bore of the piston 100.

This simultaneous communication is effected when the slide valve 103 is in its mid position in relation to the piston when the feed chamber 112 communicates through the upper feed chamber 114 with the lower part 115 of the cylinder and through the lower feed chamber 116 with the upper part 117 of the cylinder.

In turn the feed chamber 114 can communicate with passages 118 communicating with the casing of the apparatus which acts as an oil collector returning oil to the reservoir 111. The feed chamber 116 can communicate with passages 119 also communicating with the casing.

The slide valve 103 which rotates with the shaft 99 and piston 100 can be moved up and down. It is rigidly coupled to a collar 370 rotating with the shaft by a driving key 372. A second collar 371 is lodged in a groove in the rotating collar 370; the collar 371 cannot rotate but it can be given an axial movement of translation through a bell crank lever 126 coupled by a coupling rod 127 with the governor of the turbine or with a regulator. Thus by actuation of the coupling rod 127 the slide valve 103 can be given an axial movement, downwards by pushing on the rod 127, upwards by pulling on it.

In the construction above described when the slide valve 103 is in its mid position in relation to the piston oil supplied by the pump 110 flows freely through the passageways 108, 107, 112, 114, 116, 118 and 119 into the casing and back into the reservoir 111. This flow takes place under negligible pressure and very little power is required to drive the pump.

If the slide valve is moved downwardly by the linkage 127, 126, 370, 371 and 372, the supply to the chamber 114 and the lower part 115 of the cylinder is cut off while the chamber 114 is opened to the exhaust passages 118 and the casing so that pressure in 115 below the piston disappears. The communication to the chamber 116 and the upper part 117 of the cylinder is opened wider while the way to the exhaust passage 119 is closed. Pressure is therefore built up on the upper face of the piston which is thus driven downwardly following the movement of the slide valve 103 until the latter is checked, the piston following on until it reaches its mid position in relation to the slide valve when the pressure above it disappears and the piston also stops. The pressure built up on the piston during this

operation depends entirely on the resistance by the regulating rod 101 and the apparatus therefore consumes no more energy than is strictly necessary to adjust the setting and the blades and the power consumed by the pump again reaches a very low value when the valve and piston reach their relative mid position and the pressure falls.

If the rod 127 is pulled so that the slide valve 103 is raised the pressure is applied to the under face of the piston and disappears from the upper face. The piston therefore rises until in overtaking the slide valve it returns mid position in relation to the latter when its movement ceases.

It will be seen that the slide valve and consequently the regulating rod 101 are compelled to follow the vertical movements of the collars 310 and 311 actuated by the coupling rod 127.

The force necessary on the coupling rod 127 is very small because it is merely a matter of moving the balanced slide valve 103 while the force exerted by the oil under pressure acting on the faces of the piston can be as great as is necessary to adjust the blades.

Naturally the present invention is not limited to the example described. Thus for instance if a hydraulic accumulator is available for the supply of oil under pressure, the slide valve could be supplied by the accumulator but to avoid a continuous loss of oil the edges of the groove in the slide valve would have to overlap the corresponding edges of the grooves in the piston which would only be uncovered when the blades were to be adjusted.

Having now particularly described and ascertained the nature of my said invention and in what manner the same is to be performed, I declare that what I claim is:

1. An adjustment device for the vanes of a turbine or the like comprising in combination a turbine shaft; vanes carried at one end thereof; a mechanism for adjusting said vanes; an actuating rod forming part of said mechanism, the said actuating rod being disposed within a hollow portion of said turbine shaft and rotating therewith; a cylinder rotating with said turbine shaft, the said cylinder being spaced from said end of said turbine shaft; a piston movable in said cylinder and operatively connected to said actuating rod; a central bore provided in said piston; a slide rod axially movable in said central bore; a reservoir adapted to receive a pressure liquid; an axial passage provided in said slide rod communicating with said reservoir; ducts leading into said cylinder at the sides of said piston, one duct for each side, the said ducts alternatively communicating with said axial passage upon selected positions of said slide rod; ducts for returning the liquid to said reservoir, one duct for each side of said piston, the said ducts being alternatively opened and closed upon selected positions of said slide rod; means for forcing the liquid under pressure from said reservoir into said axial passage; and means for axially adjusting said slide rod whereby the liquid is caused to act upon one or the other face of said piston thereby imparting movement to said actuating rod.

2. An adjustment device for the vanes of a turbine or the like comprising in combination a turbine shaft; vanes carried at one end thereof; a mechanism for adjusting said vanes; an actuating rod forming part of said mechanism, the said actuating rod being disposed within a hollow portion of said turbine shaft and rotating therewith; a cylinder formed integral with said turbine shaft

intermediate its two ends; a piston movable in said cylinder and carried by said actuating rod; a central bore provided in said piston; a slide rod axially movable in said turbine shaft and through said central bore; a reservoir adapted to receive a pressure liquid; an axial passage provided in said slide rod and communicating with said reservoir; ducts provided in said piston and leading into said cylinder at the two sides of said piston, one duct for each side, the said ducts alternatively communicating with said axial passage upon selected positions of said slide rod; ducts for returning the liquid to said reservoir, one duct for each side of said piston, the said ducts being alternatively opened and closed upon selected positions of said slide rod; means for forcing the liquid under pressure from said reservoir into said axial passage; and means for axially adjusting said slide rod whereby the liquid is caused to act upon one or the other face of said piston thereby imparting movement to said actuating rod.

3. An adjustment device for the vanes of a turbine or the like comprising in combination a turbine shaft; vanes carried at one end thereof; a mechanism for adjusting said vanes; an actuating rod forming part of said mechanism, the said actuating rod being disposed within a hollow portion of said turbine shaft and rotating therewith; a cylinder rotating with said turbine shaft, the said cylinder being spaced from said end of said turbine shaft; a piston movable in said cylinder and operatively connected to said actuating rod; a central bore provided in said piston; a slide rod axially movable in said central bore; a reservoir adapted to receive a pressure liquid; an axial passage provided in said slide rod and communicating with said reservoir; an outlet for said axial passage; ducts provided in said piston and leading into said cylinder at the two sides of said piston, the said ducts being so disposed with respect to said outlet that they are alternatively in communication with the same in two alternative positions of said slide rod and that they are simultaneously in communication with said outlet in an intermediate position of said slide rod; ducts for returning the liquid to said reservoir, one duct for each side of said piston, the said ducts being alternatively opened and closed in the two end positions of said slide rod and being simultaneously opened in an intermediate position of said slide rod; means for forcing the liquid under pressure from said reservoir into said axial passage; and means for axially adjusting said slide rod whereby the liquid is caused to act upon one or the other face of said piston thereby imparting movement to said actuating rod.

4. An adjustment device for the vanes of a turbine or the like comprising in combination a turbine shaft; vanes carried at one end thereof; a mechanism for adjusting said vanes; an actuating rod forming part of said mechanism, the said actuating rod being disposed within a hollow portion of said turbine shaft and rotating therewith; a cylinder rotating with said turbine shaft, the said cylinder being spaced from said end of said turbine shaft; a piston movable in said cylinder and operatively connected to said actuating rod; a central bore provided in said piston; a slide rod axially movable in said central bore; a reservoir adapted to receive a pressure liquid; an axial passage provided in said slide rod and communicating with said reservoir; a pair of fluid chambers provided in said piston adjacent said slide rod, the said fluid chambers

being relatively spaced; ducts provided in said piston and extending from each of said fluid chambers to one end face of said piston; an outlet provided in said slide rod for said axial passage, the said outlet having a width to be in communication with both said ducts in an intermediate position of said slide rod and to be alternatively in communication with one or the other of said fluid chambers in two end positions of said slide rod; ducts for returning the liquid to said reservoir, one duct for each side of said piston, the said ducts being alternatively opened and closed in the two end positions of said slide rod and being simultaneously opened in an intermediate position of said slide rod; means for forcing the liquid under pressure from said reservoir into said axial passage; and means for axially adjusting said slide rod whereby the liquid is caused to act upon one or the other face of said piston thereby imparting movement to said actuating rod.

5. An adjustment device for the vanes of a turbine or the like comprising in combination a turbine shaft; vanes carried at one end thereof; a mechanism for adjusting said vanes; an actuating rod forming part of said mechanism, the said actuating rod being disposed within a hollow portion of said turbine shaft and rotating therewith; a cylinder rotating with said turbine shaft, the said cylinder being spaced from said end of said turbine shaft; a piston movable in said cylinder and operatively connected to said actuating rod; a central bore provided in said piston; a slide rod axially movable in said central bore; a reservoir adapted to receive a pressure liquid; an axial passage provided in said slide rod communicating with said reservoir; ducts leading into said cylinder at the sides of said piston, one duct for each side, the said ducts alternatively communicating with said axial passage upon selected positions of said slide rod; ducts for returning the liquid to said reservoir, one duct for each side of said piston, the said ducts being alternatively opened and closed upon selected positions of said slide rod; pump means for forcing the liquid under pressure from said reservoir into said axial passage; a bell crank pivoted to a stationary part of the device, one arm of said crank being pivoted to one end of said slide rod; and handle means pivoted to the other arm of said bell crank for imparting movement to said slide rod whereby the liquid is caused to act upon one or the other face of said piston thereby imparting movement to said actuating rod.

55

6. An adjustment device for the vanes of a turbine or the like comprising in combination a turbine shaft; vanes carried at one end thereof; a mechanism for adjusting said vanes; an actuating rod forming part of said mechanism, the said actuating rod being disposed within a hollow portion of said turbine shaft and rotating therewith; a cylinder rotating with said turbine shaft, the said cylinder being spaced from said end of said turbine shaft; a piston movable in said cylinder and operatively connected to said actuating rod; a central bore provided in said piston; a slide rod axially movable in said central bore; a reservoir adapted to receive a pressure liquid; an axial passage provided in said slide rod and communicating with said reservoir; an outlet for said axial passage; ducts provided in said piston and leading into said cylinder at the two sides of said piston, the said ducts being so disposed with respect to said outlet that they are alternatively in communication with the same in two alternative positions of said slide rod and that they are simultaneously in communication with said outlet in an intermediate position of said slide rod; ducts for returning the liquid to said reservoir, one duct for each side of said piston, the said ducts being alternatively opened and closed in the two end positions of said slide rod and being simultaneously opened in an intermediate position of said slide rod; pump means forcing the liquid under pressure from said reservoir into said axial passage; a bell crank pivoted to a stationary part of the device, one arm of said bell crank being pivoted to one end of said slide rod; and handle means pivoted to the other arm of said bell crank for imparting movement to said slide rod whereby the liquid is caused to act upon one or the other face of said piston thereby imparting movement to said actuating rod.
